UNITED STATES PATENT OFFICE.

HENRY W. JACOBS, OF TOPEKA, KANSAS, AND EDWARD D. LEVY, OF SPRINGFIELD, MISSOURI.

TANK-CAR.

1,369,111.

Specification of Letters Patent. Patented Feb. 22, 1921.

Application filed June 23, 1916. Serial No. 105,360.

To all whom it may concern:

Be it known that we, HENRY W. JACOBS and EDWARD D. LEVY, citizens of the United States, and residents of Topeka, in the 5 county of Shawnee and State of Kansas, and Springfield, in the county of Greene and State of Missouri, respectively, have invented certain new and useful Improvements in Tank-Cars, of which the following is a description, reference being had to the accompanying drawings, which form a part of our 10 specification.

Our invention relates more particularly to the discharge means, the method of securing 15 the means in place and the method of operating the same. The invention has for its object the provision of a construction whereby access to the discharge means may be had, for the purposes of repair and the like, without 20 the necessity of entering the tank, thereby obviating the delay and the danger that would otherwise be encountered.

Another object of our invention is to provide discharge means, or a valve, operable 25 from the tank car exterior, and so located and arranged that the same may be operated from the ground without the necessity of the operator climbing onto or into the tank; the discharge means being simple in design, 30 economical in construction, and adapted to be sealed against improper or unauthorized operation.

The advantages of our invention will be more clearly understood by the following 35 detailed description of the accompanying drawings, wherein:—

Figure 1 is a vertical sectional view of the lower portion of the tank car and our improved valve construction; with the valve 40 being shown in open position.

Fig. 2 is a vertical sectional view taken on the line 2—2 of Fig. 1 looking in the direction of the arrows.

Fig. 3 is a vertical sectional view of a 45 modified form of our invention; the view being taken substantially on the same line as Fig. 1, with the valve shown in closed position.

Fig. 4 is a vertical sectional view taken

on the line 4—4 of Fig. 3 looking in the direction of the arrows.

Fig. 5 is a vertical sectional view of another modification of our invention.

Fig. 6 is a vertical sectional view taken on the line 6—6 of Fig. 5.

Fig. 7 is a detail view of a portion of the center sill of the car underframe, shown in elevation, illustrating the method of sealing the valve mechanism shown in Figs. 5 and 6.

In the exemplification of our invention as 60 illustrated in the first two figures of the drawings, we show the bottom portion of a tank provided with a cast section or segmental member 10, adapted to be secured to the adjacent portions of the tank-shell 11 by means of suitable rivets 12 which are shown taken through the flanged sides of the casting or member 10 and the flanged portions of the tank-shell 11, as shown in Fig. 2.

In order to provide a fluid-tight connection, especially if the segmental member 10 is made of cast metal, we show member 10 provided with a thin sheet metal plate 13 on the inner surface thereof. The plate 13 is secured to the casting as well as to the adjoining portions of the tank-shell in any approved manner, as, for example, by means of welding indicated at 14. In the construction illustrated, the thin metal plate or covering 13 may have its sides flanged or bent downwardly so as to come intermediate of the flanged sides of casting 10 and the flanged sides of the adjacent portions of the tank-shell; or, if desired, a separate calking 85 strip may be placed intermediate of the flanged portions instead of having the same integral with the metallic plate or covering 13.

The member or casting 10 is provided 90 with depending portions or legs 15 disposed lengthwise of the tank car and adapted to be placed intermediate of the center sills 16, 16 of the tank car underframe; the casting or member 10 being provided with shoulders 95 17, 17 adapted to rest on the center sills 16, as shown in Fig. 2.

The casting or member 10 is provided with

a tapped opening adapted to receive the valve-cage or sleeve 18. The cage 18 is provided with shoulders 19 adapted to abut against the laterally disposed shoulders 17 of casting or member 10. As is evident from the construction shown, the valve-cage 18 is inserted upwardly into place; the construction being such that it may be screwed into the tapped opening in casting 10 a sufficient distance before shoulders 19 engage with the shoulders 17 on the casting 10.

The upper end of the valve-cage above the valve-seat is open-sided and extends 15 into the tank, providing suitable guiding means for the valve 20 which moves upwardly off its seat; and the valve-cage is extended downwardly to constitute a proper discharge sleeve or tube, the orifice whereof 20 is preferably in the same, or lower, horizontal plane as the bottom of the center sills 16.

The valve 20 is preferably shown in the nature of a wing-valve, so as to maintain its proper relation with the valve-cage 18 25 during movement of the valve to and from its seat.

The valve 20 is forced to its seat and maintained in closed position by a suitable spring 21 shown encircling the upwardly 30 presented valve-stem 22. The spring 21 is mounted in the upper end of the valve-cage and held in place and under proper tension by means of the spanner-nut 23, which is shown having threaded relation with the 35 upper end of the valve-cage.

The lower end of the valve 20 is shown provided with a flared or cup-portion 24 which receives the upper end of a lever 25. The cup-portion 24 permits the lever 25 to 40 have sidewise movement during operation of the valve mechanism.

At a point beneath the valve 20, namely intermediate of the discharge end of the valve-cage or sleeve 18 and the valve 20, we 45 provide a plug-valve 26, rotatably mounted in the valve-cage or sleeve 18; the latter, at this point, being formed or bulged and provided with diametrically opposite openings so as to receive the plug-valve 26 arranged 50 transversely of the cage or sleeve 18.

The plug-valve 26 is provided with an opening 27 extending diametrically therethrough, as very clearly shown in Fig. 1, so that communication may be effected between 55 the upper and lower part of the valve-cage or sleeve 18 to permit the oil to be discharged therethrough.

The lower end of lever 25 is shown pivotally connected to the plug-valve 26. The 60 end of the lever extends into the opening 27 of valve 26 and is pivotally secured to the valve. The valve 26 is provided with a suitable socket or recess, the orifice whereof is shown somewhat in the form of a T, to receive the lower end of the lever which is 65

shown provided with laterally disposed trunnions which are inserted through the upper part of the orifice; the overhanging portions at the lower end of the slot orifice, as shown at 28, hold the end of the lever in 70 place. It is evident from the construction shown that when the plug-valve is rotated toward the left in Fig. 2, the overhanging portion or lips 28 will extend across the trunnions of lever 25 and prevent the displacement of the trunnions and necessarily cause the lever 25 to be drawn downwardly 75 and out of forcing relation with the valve 20.

In order to provide sufficient play for the lever 25, the opposite wall of the opening 80 27 in plug-valve 26 is shown provided with a narrow slot 29 for the passage of lever 25 when the plug-valve 26 has been rotated to the left and into the position indicated by dotted lines in Fig. 2. The slot 29 in valve 85 26 will permit the latter to be rotated to an extent sufficient to allow valve 20 to move downwardly and completely close.

When desired, the plug-valve 26 may be surrounded by suitable bearing metal bushings, as indicated at 30. The ends of the plug-valve 26 are shown provided with trunnions 31 and 32; the trunnion 31 being preferably threaded and extending through a bearing plate or washer 33, which is held 95 in place by means of a suitable nut 34 screwing onto the threaded trunnion 31, as shown in Fig. 1. The plate or washer 33 and the nut 34, as is evident from the construction shown, will maintain the rotating member 100 or plug-valve 26 in place, (as the plug-valve 26 is shown tapering toward the end provided with the threaded trunnion 31,) and therefore prevent outward movement of the valve 26 toward the right in Fig. 1. 105

The trunnion 32 of plug-valve or member 26 is shown provided with a worm-wheel 35 which meshes with a worm 36 secured to, or formed on, the shaft 37 which is arranged transversely of the center sills 16, 16 and 110 therefore also of the depending portions or legs 15, 15 of the casting or member 10. The depending portions of the member 10 are provided with large openings, as shown in Figs. 1 and 2, which permit the passage of 115 the shaft 37. At points coincident with these openings in the depending portions of the member or casting 10, the center sills 16, 16 are also provided with openings of a size sufficient to receive the collars 38, 38 120 formed or otherwise secured to the shaft 37, as shown in Fig. 2.

The ends of the shaft 37 have suitable bearing in the bearing-members or blocks 39 and 40, which are properly secured to 125 the center sills 16, 16 and surround the openings therein. As the openings in the bearing members 39 and 40 are of a size just sufficient to receive the ends of the shaft 37, it is evident that the shaft 37 can have no 130

movement lengthwise of the shaft, because of the collars 38 which bear against the bearing members 39 and 40.

The extended end of the shaft 37 is shown 5 provided with a suitable hand-wheel 41; and the bearing member 40 is shown provided with a lug 42, see Fig. 2, which is provided with a suitable hole or orifice to receive the seal or member 43, see Fig. 2. The 10 seal or member 43 may pass through the hole or orifice in the lug 42 and around a spoke of the hand-wheel 41, as shown. With the seal member 43 arranged as just described, it is evident that the hand-wheel 41 and shaft 37 will be sealed against operation 15 and thereby prevent the accidental or improper operation of the valve mechanism until the seal has been broken.

By turning the hand-wheel 41 in the 20 proper direction, shaft 37 will be rotated so as to turn worm 36 therewith and cause the plug-valve or rotative member 26 to be rotated through the meshing of gear 35 with worm 36; the rotation of plug-valve 25 26 in anti-clockwise direction will force the lever 25 upwardly and thereby exert upward pressure on the wing-valve 20 against the action of its spring 21, inducing the valve 20 to be forced upward off its seat. 30 The rotation of plug-valve 26 in a direction which will force wing-valve 20 upward off its seat, also brings the passage 27 of the rotative member or plug-valve into proper alignment with the passage through the 35 valve-sleeve or cage 18 and thus permits a proper outflow of the oil or fluid contained in the tank. The operation just described will result in the position of the valve as illustrated in Figs. 1 and 2.

40 By rotating the plug-valve in the opposite or clockwise direction, upward pressure on lever 25 will diminish, allowing the wing-valve 20 to automatically close through the action of the spring 21, exerting constant 45 downward pressure thereon. With the valve in closed position as just described, the plug-valve 26 will assume the position very clearly shown in Fig. 3, bringing the slot 29 toward the upper part of the plug-valve 50 26 so as to afford passage for the lever 25; such rotation of the plug-valve bringing the passage 27 into a position substantially perpendicular to that illustrated in Fig. 2.

The member or casting 10, at one side of 55 the valve-mechanism, is provided with a suitable man-hole 44,—at which point, of course, the metal covering or sheet 13 is also provided with a similar hole,—of a size sufficient to permit inspection and repair of the 60 valve-mechanism located within the tank proper. The man-hole 44 is provided with a suitable cover 45, held in position in any suitable manner, as, for example, by the stud-bolts 46. The cover 45 is made fluid 65 tight in any suitable manner, as, for ex-

ample, by means of a gasket 47. The means for fastening cover 45 are preferably of such construction that the same cannot be readily loosened or removed without a proper implement or wrench. 70

In Figs. 3 and 4, we illustrate a modified form of our invention. The construction shown in these two figures, like the construction shown in Figs. 1 and 2, comprises the casting or member 10, identical with the 75 casting or member 10 in the first two figures, which forms a segment or portion of the tank; being secured to the shell of the tank in the manner previously described. The casting or member 10 is also preferably 80 shown provided with the depending walls or portions 15 adapted to extend intermediate of the center sills 16, 16, so as to provide an anchorage for the tank. The casting 10 is provided with a similar tapped opening, 85 like in the construction previously described, to receive the valve-cage or sleeve 18^a threaded so as to screw into the tapped hole in the casting or member 10; and also provided with shoulders 19 which engage 90 with the flange-portions or shoulders 17 of casting 10 and determine the proper position or extent of insertion of valve-cage 18^a into the casting or member 10. It is understood, of course, that the sleeve or valve-cage 18^a, like the cage or sleeve 18, is intended to be screwed into place from the 95 under side of the tank.

This valve construction also comprises a wing-valve 20^a, shown substantially similar 100 to the wing-valve 20, arranged to move vertically upward into the tank when forced off its seat; the valve 20^a being forced to and maintained on its seat by means of the spring 21^a arranged in the upper end of the 105 valve-cage. The spring is held by means of spanner-nut 23^a, which screws into the upper end of the valve-cage; the spanner-nut 23^a, like the spanner-nut 23 in the first two 110 figures, being provided with a central portion or hub adapted to provide bearing for the stem 22^a of the wing-valve to afford proper guidance therefor.

The valve 20^a is also shown provided with a depending flared or cup-shape member 24^a 115 which receives the upper end of a lever 25^a and permits sidewise movement of the latter during operation of the valve-mechanism.

At a point intermediate of the wing-valve 120 20^a and the discharge or lower end of valve-sleeve or cage 18^a, the latter is provided with a transversely disposed opening to afford a seat for the plug-valve or rotative member 26^a, which is preferably shown tapering 125 toward one end and surrounded with an anti-friction bushing 30^a. The bushing 30^a is provided with openings arranged in alignment with the passage extending through sleeve 18^a. The plug-valve 26^a has an open- 130

ing or port 27^a adapted to be brought into register with both ends of the passage or port extending through valve-cage or sleeve 18^a. In the construction illustrated in Figs. 5 3 and 4, the valve-mechanism is shown in closed position, so that the port or passage 27^a of the rotative member or plug-valve is disposed transversely of the valve-cage or sleeve 18^a, as clearly shown in Fig. 3.

10 The lower end of the lever 25^a extends into the port or passage 27^a, and has its lower end trunnioned in the plug-valve 26^a, to wit in one side wall of the passage or port 27^a. In order to permit the plug-valve 26^a to be 15 rotated into the position shown in Fig. 3, the plug-valve 26^a is provided with a slot 29^a which communicates with the port or passage 27^a extending through the valve, so as to permit partial rotation of the plug-valve in clockwise and anti-clockwise directions; the slot 29^a affording passage for the lever 25^a.

In order to place the valve-mechanism in open or discharging position, it would be necessary to rotate plug-valve or rotative member 26^a in anti-clockwise direction, so as to swing the passage or port 27^a into alignment with the passage or port extending through cage or sleeve 18^a. The plug-valve 26^a is 20 provided with the threaded spindle or trunnion 48 which is shown screwed into one end of the plug-valve and extends through a suitable opening provided in the center sill 16. This end of the plug-valve is also provided with a suitable plate 33^a which is shown overlapping the adjacent portion of the sleeve or valve-cage 18^a; while the spindle or trunnion 48 is shown provided with a coil spring 49, one end whereof bears against 25 plate 33^a, while the other end bears against one of the nuts 50 screwed onto the outer end of spindle or trunnion 48. This construction will prevent the plug-valve working toward the opposite or enlarged portion 40 of the opening in the valve-sleeve or cage, because the plate 33^a is held snugly against the end of the plug-valve by the spring which also abuts against the nut 50 screwed onto spindle or trunnion 48.

50 The opposite end of the plug-valve 26^a is provided with a shaft or trunnion 51, keyed or otherwise suitably secured to the valve, and extending through a suitable hole or opening in the adjacent center sill 16; having its outer end preferably squared to either receive a handwheel, as in the previously described construction, or a suitable wrench.

In order to provide suitable bearing for 60 the shaft or trunnion 51, we provide a bearing member 40^a, which may be secured to the center sill, as shown. The bearing member 40^a is provided with a seal 52, which is adapted to pass through the slot 53 arranged 65 in the shaft or trunnion 51 and a similar slot

in the member 40^a when the valve-mechanism is in closed position. The slot 53, in the trunnion or shaft 51, need not extend diametrically or straight through the shaft, but may be arranged in any desired manner, whereby both ends of the slot will register with correlated openings in the bearing 40^a when the valve-mechanism is in closed position. With this sealing mechanism, it is evident that the valve may be sealed 70 against unlawful or improper operation, as well as be held against accidental movement.

The construction illustrated in Figs. 3 and 4, is also preferably provided with a 80 manhole 44, provided with a cover 45 similar in every respect with the construction shown in Figs. 1 and 2; the cover-plate being held in place by stud-bolts 46, and the cover 45 made fluid-tight by means of a 85 suitable gasket 47.

In Figs. 5, 6 and 7, we illustrate a third modification of our invention wherein the valve-cage or sleeve 18^b is secured directly to the tank-shell, indicated at 11, by means of the flange or collar 54 which is preferably welded to the tank-shell. The flange or collar 54 is provided with a tapped opening which receives the threaded upper end of the valve-cage or sleeve 18^b. The valve-cage or sleeve is shown provided with a flange 19^b which takes against the collar and determines the extent to which the sleeve or cage may be screwed into the member 54 and also afford a fluid-tight connection. The sleeve or cage 18^b extends down between the center sills 16, where it will be protected, and has its lower end threaded to receive the usual pipe or hose-coupling.

The sleeve or cage 18^b is provided with 105 the wing-valve 20^b adapted to move vertically off its seat against the action of the spring 21^b surrounding the stem 22^b of the valve in the upper part of the cage. The spring 21^b, like in the previously described 110 constructions, is held in position by the spanner-nut 23^b which is shown screwed into the upper end of the valve-cage and provided with a central hub-portion through which the stem 22^b extends.

The bottom of the valve 20^b is shown provided with a cup-portion 24^b which receives the upper end of a lever 25^b; the cup-extension 24^b permitting lateral play or movement at the upper end of the lever.

The lower end of the valve-sleeve 18^b is shown provided with a transversely disposed shaft 55, see Fig. 6, one end whereof has bearing in the side wall of the sleeve 18^b. The sleeve is preferably shown provided with a boss to provide sufficient bearing for the inner end of the shaft 55. The other end of the shaft extends through a suitable opening formed in the side wall of the sleeve 18^b, and is provided with a flange 125 130

or collar 56. The end of the shaft 55, adjacent the flange or collar 56, is preferably provided with a plug 57, shown screwed into the enlarged portion or boss formed on the 5 side of the valve-sleeve or cage; and the plug 57 is provided with a gland 58; both plug and gland permitting the shaft to extend therethrough. With collar 56 taking against the plug 57, which has screw-connection with the sleeve or cage 18^b, it is apparent that the shaft 55 will be held against movement lengthwise of the shaft. In the particular exemplification shown in Fig. 6, the shaft 55 is shown provided with an extension 55^a, preferably removably secured to the end of the shaft. The extension 55^a has bearing in the bearing 40^b, bolted or otherwise secured to the center sill 16. The bearing-member 40^b is provided with a lug 20 59, adapted to be engaged by the pin 60 secured to the shaft-extension 55^a, and provide a stop whereby too far rotation of the shaft in either direction will be prevented. The outer end of shaft-extension 55^a is 25 squared to receive a hand-wheel or suitable wrench whereby rotation of the shaft may be accomplished.

The shaft 55, at a point within the valve-cage or sleeve 18^b, is provided with a crank 30 or arm 61, to which the lower end of lever 25^b is pivotally secured in any suitable manner, as, for example, by a cross-pin removably held in place by a cotter as shown in Fig. 6. In order to permit sufficient rotation of shaft 55 in a direction to firmly seat valve 20^b, the lower end of lever 25^b is 35 slightly curved or bent to extend about the shaft.

The valve 20^b in Figs. 5 and 6 is shown in 40 closed position, and in order to open the valve or force the same upwardly off its seat, it is necessary to rotate shaft 55 in anti-clockwise direction in Fig. 5. This will cause crank 61 to force lever 25^b upwardly, thereby forcing valve 20^b against the action of spring 21^b.

In order to prevent the unauthorized manipulation of the valve-mechanism, we provide bearing 40^b and the shaft-extension 55^a 50 with openings adapted to register when the valve is in closed position. The registered holes are intended to receive any suitable sealing means, as, for example, the usual seal composed of a metallic band or wire 62, whose ends are sealed together, as shown in Fig. 7.

Adjacent the valve-mechanism described, the tank-shell is shown provided with a man-hole 44^a.

60 In this construction, where no sectional member or casting is employed as in the previously described constructions, the man-hole is shown preferably welded to the tank-shell like the collar or flange 54. Both the 65 man-hole 44^a and the flange 54, however, may

be riveted or otherwise secured to the tank-shell.

The man-hole 44^a is provided with a cover or plate 45^a shown secured in place by the stud-bolts 46, as in the other construction. 70

We prefer to locate the valve-mechanism as shown, namely at a point intermediate of the center-sills, and yet at the same time operable from a point intermediate of the center sills and the car-side where it is easily accessible; obviating the necessity of climbing on top of the tank-car as is the case with some of the constructions at present employed. The constructions shown and herein described, we believe to be the simplest 75 embodiments of our invention; certain modifications in details of construction may, however, be made without departing from the spirit of our invention, and we do not wish to be understood, therefore, as limiting 80 ourselves to the exact constructions shown and described. 85

What we claim is:—

1. In a tank car, a valve-cage terminating in a discharge conduit, with the upper end 90 removably secured to the tank and extending thereinto, a self-seating valve mounted in the upper end of said cage, and means mounted on the car underframe and disposed transversely of said discharge conduit 95 whereby the valve may be controlled from the tank exterior.

2. In a tank car, a valve-cage terminating in a discharge conduit for the tank, the valve-cage being removably secured to the 100 tank intermediate of the center sills of the car underframe, a self-seating valve slidably mounted in said cage, and rotative means mounted on the center sills of the car underframe whereby said valve may be controlled. 105

3. A tank car, provided with a removable valve-cage constituting a discharge and depending intermediate of the center sills of the car underframe, a self-seating valve slidably mounted in the cage, a plug-valve rotatably mounted in the discharge end of said cage and operatively connected with the first valve, and rotative means mounted on the center sills whereby said valve may be moved off its seat. 110

4. A tank car provided with a cast section in the bottom thereof, having depending portions adapted to come intermediate of the center sills of the car underframe, said cast-section being provided with a tapped opening into the tank, a valve-cage removably secured in said tapped opening and terminating in a discharge conduit, a spring-controlled valve mounted in the upper part of said valve-cage and closable in the direction of flow, a plug-valve rotatably mounted in the valve-cage beneath the first mentioned valve, a lever pivotally mounted on the plug-valve and having operative relation with the first valve, and means mounted on the cen- 120 125 130

ter sills of the car underframe, adapted to be locked thereto, whereby said plug-valve may be rotated and the first mentioned valve moved off its seat.

5. 5. A tank car, provided with an apertured casting at the longitudinal center of the tank, adapted to come intermediate of and in engagement with the center sills of the car underframe, a valve-cage removably secured 10 in the aperture of said casting and having a valve-seat, said cage being elongated and constituting a discharge conduit depending between the sides of said casting, a spring-controlled wing-valve mounted on said seat 15 and closable in the direction of flow, a plug-

valve rotatably mounted in the lower part of said valve-cage, a lever pivotally connected to said plug-valve and in operative engagement with said wing-valve whereby the latter is forced upwardly when the plug- 20 valve is rotated into open position, and means secured to the center sill of the car underframe for rotating said plug-valve, said means being adapted to receive a seal when the valves are in closed position.
